(57) CLAIM

An ornamental design for an under-cabinet paper plate dispenser as shown.

DESCRIPTION

FIG. 1 is a perspective view of an under-cabinet paper plate dispenser;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines shown in FIG. 7 depicts portions of the invention that form no part of the claimed design.

1 Claim, 7 Drawing Sheets
